INVENTOR

BY *John New York*

ATTORNEY.

UNITED STATES PATENT OFFICE.

SAMUEL ROWAN, OF NEW YORK, N. Y.

DESIGN FOR A BRUSH-BACK.

SPECIFICATION forming part of Design No. 20,857, dated June 23, 1891.

Application filed May 6, 1891. Serial No. 391,821. Term of patent 3½ years.

To all whom it may concern:

Be it known that I, SAMUEL ROWAN, a citizen of the United States, residing at New York city, in the State of New York, have invented and produced a new and original Design for a Brush-Back, of which the following is a specification, reference being had to the accompanying drawing, forming part thereof.

The figure is a view of the back of a hair-brush, showing the ornamentation thereon, the design consisting of scroll, shell, and flower ornamentation.

This design forms a border on the back of

the brush, as shown. It is intended to be carved in the material of the backs of the articles as a border or stamped or cast therein. I do not claim any one of these features of the design alone, but the grouping of the same, as shown in the drawing.

20

I claim—

The design for a brush-back, substantially as shown.

SAMUEL ROWAN.
